(57) **CLAIM**

The ornamental design for an appliance head, as shown and described.

DESCRIPTION

FIG. 1 is a top, front, right side perspective view of an appliance head showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, showing the claimed design attached to an appliance body which is shown in broken lines.

The details shown in broken lines are for illustrative purposes only and form no part of the claimed design.
